UNITED STATES PATENT OFFICE.

DAVID R. KEITH, OF FORT SCOTT, KANSAS.

AUTOMATIC FUEL-FEEDER.

1,066,281.

Specification of Letters Patent.

Patented July 1, 1918.

Application filed July 13, 1912. Serial No. 709,184.

To all whom it may concern:

Be it known that I, DAVID R. KEITH, a citizen of the United States, residing at Fort Scott, in the county of Bourbon and State of Kansas, have invented new and useful Improvements in Automatic Fuel-Feeders, of which the following is a specification.

The invention relates to a mechanical stoking apparatus, and more particularly to the class of automatic fuel feeders for boilers or other furnaces.

The primary object of the invention is the provision of a feeder of this character wherein a rotor will distribute fuel uniformly over the grate surface of a furnace so that the finer particles of fuel are consumed in the transit of the supply over the fuel bed.

Another object of the invention is the provision of an automatic feeder of this character, wherein fuel will be uniformly spread over the fuel bed of a furnace so that the carbon of the fuel will become intermingled with the gases from the fuel bed, thereby assuring perfect combustion, the smoke being consumed by the rotor when distributing the fuel.

A further object of the invention is the provision of an apparatus of this character which can be readily attached to the front wall of a furnace so as not to interfere with the hand firing and which will permit access to be had to the furnace during its operation.

A still further object of the invention is the provision of an automatic feeder of this character in which the smoke ordinarily present within the fire box of a furnace will be entirely eliminated as the fuel is distributed in the form of a spray over the fire of the furnace, and thus the entire charge of fuel will be burned thereby, avoiding the possibility of waste, as the uniform distribution of the fuel over the fuel bed permits the entire consumption both of the large and small particles of the fuel.

A still further object of the invention is the provision of an automatic feeding device of this character in which all kinds of fuel may be properly fed into the furnace, so as to be consumed thereby and for the perfect combustion of the same, the device being automatic in its action, and is capable of regulation for the proper feeding of the fuel to the furnace.

A still further object of the invention is the provision of an automatic feeder of this character which is simple in construction, thoroughly reliable and efficient in its purpose, and inexpensive in manufacture.

With these and other objects in view the invention consists in the construction, combination and arrangement of parts as will be hereinafter more fully described, illustrated in the accompanying drawings, and pointed out in the claims hereunto appended.

In the drawings: Figure 1 is a fragmentary front elevation of a furnace of the boiler type showing the automatic feeder constructed in accordance with the invention mounted thereon, the casing being removed. Fig. 2 is a fragmentary vertical longitudinal sectional view through the furnace and feeder. Fig. 3 is a sectional view on the line 3-3 of Fig. 1. Fig. 4 is a top plan view of the feeder. Fig. 5 is a side elevation of the rotor.

Similar reference characters indicate corresponding parts throughout the several views in the drawings.

Referring to the drawing by numerals, 10 designates a portion of a boiler furnace which is of the ordinary well-known construction provided with a fire box 11 in which are arranged the usual grate bars 12 affording a fuel bed, the front wall of the furnace being equipped with spaced pairs of upper and lower doors 13 and 14 respectively, whereby access may be had both to the fire box 11 and the ash pit 15 of the said furnace as usual.

The automatic fuel feeder comprises a base plate 16 which is secured to the front wall 95 of the furnace between the doors 13 and 14 by means of bolt members 17 although the said plate may be fastened in any other suitable manner if desired, and supports a pair of brackets 18, on which is detachably bolted a rotor casing 19 from which rises a hopper 20 into which is introduced fuel adapted to be fed into the fire box 11, of the furnace.

Arranged within the rotor casing 19 is a 105 rotor comprising a blade wheel 21, each blade 22 thereof being provided with a fuel distributing pocket or cup 23 at its outer free end, while at the center of the wheel is formed a hub 24 provided with a squared 110 central aperture 25 in which is received the upper squared end of a rotatable shaft 26

journaled in bearings 27 bolted or otherwise secured to the base plate 16, the said shaft 26 being vertically disposed and the rotor is detachably fastened thereto through the 5 medium of a lock nut 28 threaded on the upper end of the said shaft, while fixed to the opposite end of the latter is a beveled gear 29 meshing with a beveled pinion 30 fixed to a horizontally disposed driven shaft 10 31 the same being journaled in bearings 32 carried by the base plate 16 the driven shaft 31 being operated upon by any suitable motive power whereby rotary motion will be imparted to the rotor for the distribution 15 of fuel received within the pockets or cups 23 thereof into the fire box 11 of the furnace.

The hopper 20 is detachably connected to the top of the casing 19 by means of bolt 20 members 33, so that the said hopper can be readily removed to permit access to be had to the rotor thereby enabling the cleaning or repairing of the same when required. It is of course understood that the top of the 25 rotor casing 19 is formed with a central opening 34 for establishing communication between the hopper 20 and the rotor so that fuel contained within the hopper will be delivered into the rotor for distribution thereby 30 into the fire box 11 of the furnace. The fuel fed from the hopper 20 into the rotor will be uniformly distributed thereby over the entire fuel bed within the fire box of the furnace.

35 Mounted upon the base plate 16 and inclosing the shafts and gear connections therebetween is a hood or covering 35 which conceals the same and thereby excludes dust and other foreign matter therefrom. It will 40 be noted that the doors 13 and 14 can be readily opened to permit access to be had to the interior of the furnace without interference from the automatic feeding device. Slidably fitted within the discharge 45 hopper 20 is a cut-off slide 36 whereby the quantity of fuel to be discharged into the rotor can be regulated as the occasion may require. It will be noted that the rotor casing 19 is positioned in a plane elevated 50 above the plane of the fuel bed, so that the fuel will be thrown within the fire box 11 on the rotation of the rotor due to centrifugal force, thereby spreading the said fuel so that it leaves the surface of the rotor in a 55 uniform spray falling over the entire grate surface and in this manner assuring perfect combustion and entirely eliminating the presence of smoke during the stoking of the furnace. It will be apparent that when the 60 fuel is being distributed and spread by the

rotor the minute particles of fuel will be consumed in transit over the fuel bed and the carbon of the fuel will be intermingled with the gases from the burning fuel of the bed.

6 From the foregoing description, taken in connection with the accompanying drawings, it is thought that the construction and operation of the invention will be clearly understood, and therefore, a more extended 7 explanation has been omitted.

What is claimed is:—

1. In an automatic feeder the combination with a furnace wall having an inlet opening, of a base plate fixed to said wall, 7 alining bearings arranged in pairs at right angles to each other, a driving shaft journaled in one pair of bearings, a driven shaft journaled in the other pair of bearings, gear connections between the shafts, brackets extending outwardly from the base plate, a rotor casing supported upon said brackets and having an open side coextensive with the opening in the wall, a rotor fixed to the driven shaft and located within the said casing, inwardly tapering pockets formed on and projecting radially from the rotor, one wall of each pocket terminating short of the center of said rotor to provide an opening at the inner end and at one side of the 8 pocket, and a feed hopper rising from the casing and communicating therewith.

2. In an automatic feeder the combination with a furnace wall having an inlet opening, of a base plate fixed to said wall, alining 9 bearings arranged in pairs at right angles to each other, a driving shaft journaled in one pair of bearings, a driven shaft journaled in the other pair of bearings, gear connections between the shafts, brackets extending outwardly from the base plate, a rotor casing supported upon said brackets and having an open side coextensive with the opening in the wall, a rotor fixed to the driven shaft and located within the said 1 casing, inwardly tapering pockets formed on and projecting radially from the rotor, one wall of each pocket terminating short of the center of said rotor to provide an opening at the inner end and at one side of the 1 pocket, a feed hopper rising from the casing and communicating therewith, and a cut-off slide arranged within the hopper.

1 In testimony whereof I affix my signature in presence of two witnesses.

DAVID R. KEITH.
